UNITED STATES PATENT OFFICE

137,770

DESIGN FOR A DRESS

Marion McCoy, St. Louis, Mo.

Application March 24, 1944, Serial No. 113,024

Term of patent 3½ years

(Cl. D3—26)

To all whom it may concern:

Be it known that I, Marion McCoy, a citizen of the United States, residing in St. Louis, in the county of St. Louis City and State of Missouri, have invented a new, original, and ornamental Design for a Dress, of which the following is a specification, reference being had to the accompanying drawing, forming part thereof.

I claim:

The ornamental design for a dress, substantially as shown.

MARION MCCOY.
